(57) **CLAIM**

The ornamental design for a brake caliper, as shown and described.

DESCRIPTION

FIG. 1 is a bottom perspective view of a brake caliper showing one embodiment of my new design;

FIG. 2 is a bottom view thereof;

FIG. 3 is a top view thereof;

FIG. 4 is a left side view thereof;

FIG. 5 is a right side view thereof;

FIG. 6 is a front view thereof;

FIG. 7 is a back view thereof;

FIG. 8 is a top perspective view thereof;

FIG. 9 is a bottom perspective view of a brake caliper showing another embodiment of my new design;

FIG. 10 is a bottom view thereof;

FIG. 11 is a top view thereof;

FIG. 12 is a left side view thereof;

FIG. 13 is a right side view thereof;

FIG. 14 is a front view thereof;

FIG. 15 is a back view thereof; and,

FIG. 16 is a top perspective view thereof.

The broken lines deict portion of the brake caliper which form no part of the claimed design.
